(57) **CLAIM**

The ornamental design for a display screen with animated graphical user interface, as shown and described.

DESCRIPTION

FIG. 1 is a front view showing the first image in a sequence of a display screen with animated graphical user interface; and,

FIG. 2 is a front view of a second image thereof.

The appearance of the transitional image sequentially transitions between the images shown in FIGS. 1-2. The process or period in which an image transitions to another image forms no part of the claimed design. The dark and light gray elements in the drawings, either in line segment shape or in irregular block shape, indicate contrasts in appearance, and form part of the claimed design.

The dot-dash-dot line showing of a display screen, the dash-dash broken line showing the features within the interface (including a human figure), and the dash-dash broken line in dark gray scale are included for the purpose of illustrating environmental structure and form no part of the claimed design.
